CONSOLE GASOLENE DISPENSING UNIT

Leonard N. Freed, Saddle Brook, N.J., assignor to Cities Service Oil Company, Bartlesville, Okla., a corporation of Delaware

Original design application June 29, 1964, Ser. No. 80,621, now Patent No. 205,086, dated June 21, 1966. Divided and this application June 13, 1966, Ser. No. 3,332

Term of patent 14 years

(Cl. D52—2)

FIG. 1

Fig.2

Fig.3

FIGURE 1 is a perspective view of a console gasolene dispensing unit showing my new design.

FIGURE 2 is an elevational view taken from one side thereof, the opposite side being a mirror image of the side shown.

FIGURE 3 is an elevational view taken from one side of a modified form of the console gasolene dispensing unit shown in FIGURE 1, the opposite side being a mirror image of the side shown.

This is a division of design application Ser. No. D.80,621, filed June 29, 1964, now Design Patent No. D.205,086.

The essential features of the design reside in the portions shown in full lines.

I claim:

The ornamental design for a console gasolene dispensing unit, substantially as shown and described.
